CONTAINER

Lyman L. Jones, Seattle, Wash., assignor to American Can Company, New York, N. Y., a corporation of New Jersey

Application January 12, 1940, Serial No. 313,614

2 Claims. (Cl. 220—44)

The present invention relates to sheet metal containers and has particular reference to an escapement valve or venting device for use in containers filled with products that may develop gases or with contents that may be subjected to volumetric changes.

An object of the present invention is the provision of an escapement or blowout valve for the can top of a hermetic sealed container which permits escape of entrapped air or gas from within the container or permits expansive changes in the can contents as for such products as frozen foods thus preventing bursting of the can while at the same time providing an indication of the defective character of the product.

Another object of the invention is the provision of a blowout device which is arranged to relieve any excess pressure generated within a filled container as for such products as tobacco sealed in gas but which will not permit the ingress of air into the container.

Another object of the invention is the provision of a hermetic seal including a blowout disc which is of simple construction, economical in cost and one that is readily assembled on the outside wall of a can end by the can maker, the end being sealed onto its filled container by means of standard sealing equipment in the packer's plant, or can maker's plant.

Numerous other objects and advantages of the invention will be apparent as it is better understood from the following description, which, taken in connection with the accompanying drawing, discloses a preferred embodiment thereof.

Referring to the drawing:

Figure 1 is a fragmentary perspective view of a sheet metal container embodying the present invention and illustrates a closure disc sealed in position upon the container top; and

Fig. 2 is an enlarged fragmentary vertical sectional view taken substantially along the line 2—2 in Fig. 1 and illustrates a disc closure in closed position and sealed upon a filled container.

The present invention contemplates the packing of frozen food products in sheet metal containers and it is desirable in such practice to reduce the clearance or gas space to accomplish efficacious or quick freezing of the product. This, however, subjects the metal container to severe strains by the expansion of the product during freezing thus causing the container to bulge outwardly and this often breaks the seams or joints of the container.

It is the purpose of this invention to provide a vent in a part of a container and to normally retain the vent closed by a metal disc closure. This vent however will relieve any excess pressure generated or will allow for volumetric changes within a container, after which relief the disc closure will reseal the opening.

A preferred embodiment of the invention as illustrated in the drawing, comprises a round sheet metal container having a tubular body 11, the ends of the blank from which the body is formed being joined together by a side seam 12 (Fig. 1). The ends of the container are or may be substantially the same and for the purpose of the invention only a top end member 13 is shown. The top end member is secured to the tubular body by a double seam 14. This double seam joint may be lined with a gasket or sealing compound 15 (Fig. 2) in the usual manner to render the joint hermetic.

The top end member has a substantially flat upper surface below the surrounding rim of the double seam 14 and has a countersunk panel 16, located centrally of the end. The panel wall is cut through with a circular vent 17. An annular depending merging wall section 18 provides a surrounding wall for the countersunk panel 16 and is of suitable dimension to frictionally engage with the outer diameter of a disc closure 19. Such friction normally retains the closure in position, thereby covering and sealing the vent 17.

The disc closure 19 is preferably made of metal to substantially fill the countersunk panel 16 to provide a flush top surface for the top end 13. A gasket 20 may be inserted within the countersunk panel 16 and beneath the disc closure 19 to produce a hermetically sealed closure. It is sometimes desirable to dispense with the gasket lined metal closure and substitute a rubber disc instead.

The disc closure 19 may be further secured to the can end and is sealed in position upon the countersunk panel 16 by a moistureproof cellulose sticker element 21. This sticker is preferably transparent and is shown rectangular in shape as such a shape facilitates rapid feeding and cutting of strip stock from which the sticker is made. The cellulose sticker may be made from moistureproof "Scotch" tape or Cellophane coated with lacquer and adhesively secured over the disc closure 19 and the adjoining parts of the end 13 which surround the opening.

Figure 2 of the drawing shows a filled con-

tainer with a product 22 over the top of which is left a clearance or head space 23 which may be filled with a gas. If the clearance space 23 is filled with gas the pressure of the gas, in the case of frozen foods for example, may be at atmospheric or it may be below or above depending upon the temperature. Moderate temperature changes will cause the food product to expand thereby reducing the clearance space. Rapid and severe temperature changes will subject the food products to volumetric changes, increase the internal pressure and cause such expanding frozen product to force the disc closure from the container. If the developed pressure is sufficient this will emit a certain amount of the food product through the vent. The cellulose sticker 24 remains attached to the disc closure and to the engaged part of the can end 13. Upon return to normal temperature and pressure, the disc closure 19 will again seat itself over the vent 17 and this prevents the ingress of air into the container.

A product such as tobacco may be packaged within this type of container. The clearance space 23 would then be filled with a gas under a slight pressure but not sufficient to disturb the seal. However development of greater pressures in a filled can of this type would cause the escape of excess pressure through the vent 17 without permitting the entrance of air into the container.

It should be evident, from the above description, that such a valve construction can also be used for containers filled with gas producing products such as cheese and the like. For a cheese filled can, the vent 17 will operate as a relief valve for the excessive gas as it is generated.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A sheet metal container comprising a tubular body having top and bottom end members 50

secured thereto, one of said end members being substantially flat and having a shallow countersunk panel portion provided with a vent opening, said panel portion being surrounded by a substantially vertical peripheral wall, a substantially flat imperforate rigid disk closure element disposed in said panel portion and lying substantially in the plane of the adjacent end member, said disk element having peripheral frictional engagement with said wall for normally covering and closing the opening, and a cellulose sticker element disposed over and entirely covering said disk closure element and secured to adjacent portions of said container end for movably confining said closure within said panel, said sticker element being flexible under excess internal pressure to permit said disk to move outwardly and unseal said opening to vent the container peripherally of the disk closure without separation of said closure from the container end.

2. A sheet metal container for preserving expansible products or which develop gases and wherein a head space is present in the filled can, comprising in combination: a tubular body having top and bottom end members secured thereto in an hermetic seam including a surrounding rim, said top end member having a substantially flat surface located below the upper edge of said rim and having a shallow countersunk panel with a vent opening disposed therein, said shallow countersunk panel being surrounded by a substantially vertical peripheral wall, an imperforate rigid metallic disk closure disposed in frictional engagement within said wall for normally covering said opening, said closure substantially filling said shallow panel to present a flush top surface, and a cellulose sticker sheet disposed over said disk closure and adhesively secured to adjacent portions of said top end for movably confining the closure within said panel, said sticker being flexible and yieldable under excess internal pressure to temporarily unseal said opening to compensate for expansion of the contained product and to permit escape of generated gases in said head space of the container peripherally of the disk closure, said adhesively secured sticker sheet preventing ingress to the container of outside atmosphere.

LYMAN L. JONES.
